UNITED STATES PATENT OFFICE.

WILLIAM C. HAYMAN, OF SCHENECTADY, NEW YORK, ASSIGNOR TO GENERAL ELECTRIC COMPANY, A CORPORATION OF NEW YORK.

HIGH-TENSION UNDERGROUND CABLE.

Application filed October 25, 1927. Serial No. 228,646.

The present invention relates to multiple conductor high tension underground cable and has for its object to provide fillers therefor of improved construction to the end that gas may be excluded from the interior of the cable as completely as possible.

For a consideration of what I believe to be novel and my invention, attention is directed to the accompanying description and the claims appended thereto.

In the attached drawing which is illustrative of my invention, is shown in cross-section a three-conductor cable.

For the purpose of specifically illustrating my invention, I have shown it in connection with a 25,000 volt three-conductor cable but it is not to be understood as being limited thereto or to the particular shape of the conductors although the arrangement of the latter is particularly advantageous in a cable of this character.

Each conductor is composed of a central conductor member 1 which is segmental in cross-section, and snugly surrounding it is a plurality of smaller conductors 2 which are laid up in any suitable way so that the conductor as a whole is self-supporting. Surrounding each of the conductors thus formed are numerous layers of insulation 3, said layers being composed for example, of relatively narrow, tightly-wound strips or ribbons of tough paper, the joint between adjacent strips in one layer being covered by other strips both above and below it.

The conductors are assembled in a well-known manner to form a body in which they are spaced 120° apart. Surrounding the conductors and their individual insulations is an annular covering or belt of insulation 4 which may also be formed of paper and wound on in the manner described for the individual conductors. Outside of the belt insulation is a lead sheath 5.

Between the conductors thus assembled both at the center and adjacent the belt insulation are spaces 6 in which are located fillers. It is to the construction of these fillers that my invention is specifically directed. The commonly accepted arrangement is to make these fillers wholly of jute in the form of relatively hard twisted cords or to make them wholly of paper. Both of these are objectionable because the material does not properly pack. Owing to the fact that the places where the insulating

covering and the belt insulation contact wedge-shaped spaces or openings are formed and to the fact that the jute cords are round and of considerable size they do not properly fill the spaces and as a result small voids are formed in which gas can and does collect with the result that ionization takes place in these regions. When paper alone is used it also fails to completely fill the spaces between the conductor coverings due wholly or in large part to the lack of resiliency of the paper.

I overcome the objection above noted by using a filler which is composed of three distinct elements instead of one. The sides of each filler where the space between the belt and conductor coverings contracts to the proportions of a knife edge as indicated at 7, are composed of paper strips 8 and for that purpose I have found kraft paper to be satisfactory. The paper is cut into relatively wide strips and is passed through a suitable machine which crumples it and at the same time gives to it a wedge-like formation in cross-section and of any suitable length. The paper may take the form of a paper cord or twine and be given the wedge-like formation as the conductors are passed through a forming or sizing die in the cable assembling operation. Between two of these wedge-like strips is located a sufficient number of jute cords 9, to fill the remainder of the space. The number of these cords and the size thereof will vary for different size cable as will be readily appreciated. Since the jute cords are somewhat elastic they serve to firmly press the side paper members laterally into the wedge-like openings with the result of completely filling the spaces between conductor coverings and the belt insulation. For the central space between the conductors I also employ a filler of crumpled kraft paper 10 which in the assembling operation is made to completely fill the central region between them. For this purpose it is preferable to use a number of pieces of paper cord or twine which extend lengthwise of the cable and the pressure of the sizing or forming die squeezes the paper to the shape indicated.

For simplicity of description, I have referred to the fillers in the positions they occupy after the cable parts are assembled. In making the cable each of the conductors is first insulated, then they are laid up or as-

sembled with the central filler between them, and the paper and jute fillers in the outer spaces. The conductors and the fillers are then passed through a sizing die which compresses them, after which the belt insulation is tightly wound thereon. The cable is then thoroughly impregnated with a suitable compound, as heavy oil, for example, in any suitable manner, after which the lead sheath is applied. Due to the elasticity of the jute the paper wedges or members are forced laterally, which action is in part due to the sizing die and the wound-on belt insulation and the paper, and completely fill the wedge-like portions of the filler spaces. Any minute spaces or voids are filled with the compound or fluid with which the paper insulation and the fillers are impregnated.

What I claim as new and desire to secure by Letters Patent of the United States, is:—

1. In a cable, the combination of a number of separately-insulated conductors, a belt of insulation which surrounds the conductors and binds them together, and fillers for the spaces between the conductor coverings and the belt insulation, each of which comprises side members which are made of paper and a central member located between the side members and which is made of jute.
2. In a cable, the combination of a number of separately-insulated conductors, a wrapping of paper which forms the belt insulation and binds the conductors together, and fillers for the spaces between the conductors and the belt insulation, each of

which comprises two side members which are made of kraft paper and are wedge-shaped in cross-section and a central member located between the side members which is composed of jute cords.

40

3. In a cable, the combination of a number of separately-insulated conductors, a belt of paper insulation which tightly surrounds the conductors and binds them together, fillers for the spaces between the conductors and the belt insulation, each of which comprises side members which are made of paper and are wedge-shaped in cross-section, and a member located centrally between the wedge members which is made of jute, an impregnating fluid for the insulation and fillers, and a fluid-tight metallic sheath which encloses the belt insulation.

45

4. In a cable, the combination of a number of separately-insulated conductors, a body of paper located within the space defined by the contacting surfaces of the conductor insulations and filling the same, a belt of insulation which surrounds the conductors and binds them together, and fillers for the spaces defined by the conductor insulations and the belt insulation, each of said fillers comprising wedge-shaped side members made of paper and a member centrally located between the side members and made of jute, said jute exerting side-wise pressure on the paper members.
